PUMP TYPE DART GUN

John J. Gora, River Rouge, and Edward J. Wy-
rick, Wyandotte, Mich., assignors to All Metal
Products Company, Detroit, Mich., a corpora-
tion of Delaware

Application March 25, 1940, Serial No. 325,751

1 Claim. (Cl. 124—16)

The present invention relates to guns and particularly relates to toy guns adapted to shoot darts.

One of the primary objects of the present invention is to provide an improved gun of the type mentioned which is shaped to simulate a rifle having pump means for cocking the same.

Another object of the invention is to provide an improved gun of the type mentioned having an improved pump action means whereby the projecting spring is compressed to cock the gun and is then latched in cocked position while the pump grip or handle is then returned to its initial position.

Another object of the invention is to provide an improved means whereby the dart is held in the gun and cannot accidentally drop therefrom until the trigger releases the projecting spring.

Another object of the invention relates to improvements in the construction and arrangement of the elements whereby the gun construction may be economically manufactured.

Other objects of the invention will become apparent from the following specification, the drawings relating thereto and from the claim hereinafter set forth.

In the drawings, in which like numerals are used to designate like parts in the several views throughout:

Figure 1 is a side elevational view of a toy gun embodying features of the present invention;

Fig. 2 is a vertical cross-sectional view taken longitudinally of a portion of the gun illustrated in Fig. 1, with the elements in one position;

Fig. 3 is a view similar to Fig. 2, illustrating the elements in another position when the projecting spring has been compressed to cocked position;

Fig. 4 is a view similar to Fig. 3, showing the parts in another position, when the pump grip has been returned to its initial position after the gun has been cocked;

Fig. 5 is a front elevational view taken in the direction of the arrow 5 of Fig. 2;

Fig. 6 is a cross-sectional view taken substantially along the line 6—6 of Fig. 2;

Fig. 7 is a cross-sectional view taken substantially along the line 7—7 of Fig. 2;

Fig. 8 is a cross-sectional view taken substantially along the line 8—8 of Fig. 2;

Fig. 9 is a cross-sectional view taken substantially along the line 9—9 of Fig. 2;

Fig. 10 is a cross-sectional view taken substantially along the line 10—10 of Fig. 2; and

Fig. 11 is a fragmentary cross-sectional view 55

taken substantially along the line 11—11 of Fig. 2.

Referring to the drawings, the toy gun which is illustrated is shaped to simulate a rifle having a stock 10 connected to the frame portion 12 of a sheet metal casing which is shaped to provide a barrel 14.

The barrel 14 is shaped to provide an upper longitudinally extending chamber 16 and a lower longitudinally extending chamber 18 which intercommunicate through the reduced neck portion 20 therebetween. The chambers 16 and 18 are generally circular in shape, and the lower chamber 18 is provided with a longitudinally extending slot 22 on the underside thereof.

A longitudinally extending tubular member 24, which is generally circular in cross section and which has a longitudinally extending slot 26 formed in the top thereof, is mounted within the chamber 18 within the forward end thereof. The member 24 is mounted in spaced relation with the walls of chamber 18 with the axis of both substantially coinciding, and the forward end thereof is mounted on a washer 28 having a central opening 30 therethrough. The washer 28 is provided with outwardly extending tabs 32 which extend through corresponding slots or apertures formed in the barrel 14 adjacent the forward end thereof. Inwardly struck tabs 34 are formed on the forward edge of the barrel at spaced intervals therearound and bear against the front face of the washer 28 so that it is fixed with respect to the casing.

The rear end of tubular member 24 is provided with out-struck tabs 36 at diametrically opposed points which serve to space the rear end of the member 24 from the side walls of the chamber 18 and abut against in-struck tabs 38 formed in the wall of chamber 14 so that the tubular member 24 is fixed with respect to the casing.

A spiral spring 40 is mounted in embracing relationship to the tubular member 24 with the innermost convolution of the spring abutting against the tabs 36 so as to limit movement of the spring and so that the spring is compressible and expansible longitudinally of the barrel. The forwardmost convolution of the spring is adapted to bear against a washer 42 which slidably embraces the tubular member 24 and which has a radially inwardly extending tab 44 formed thereon which is adapted to project through the longitudinally extending slot 26.

The spring 40 is adapted to be compressed to its cocked position by means of pump means which are slidable longitudinally of the barrel.

Such pump means include an elongated generally U-shaped sheet metal member 46, the upper edges of which terminate in outwardly disposed flanges 48. The upper edge of member 46 is slidably received within the lower end of chamber 18, through the elongated slot 22, and the flanges 48 are adapted to slidably bear along the in-turned edges of the slot 22, as best shown in Figs. 7 and 8.

A pump handle or grip 50 is secured to the member 46 adjacent the rear end thereof. The member 50 is provided with a U-shaped recess 52, which receives the member 46 therein, and such member 46 is provided with a depending struck-out portion 54 which extends through an aperture in the member 50 and terminates in out-struck tabs 56 so that the handle 50 is securely attached to the member 46. It will thus be seen that by grasping the handle and pulling it toward the stock, the member 46 will slide on the flanges 48 with respect to the barrel 14.

The forward end of the member 46 is provided with upstanding projections at each side thereof. The projection on one side is indicated at 58 and is curved about the tubular member 24 on a curvature about the center of the barrel. The opposite edge is provided with a projection 60, which is complementary in shape to the projection 58. The projection 60 terminates in an upwardly extending straight portion 62 which extends through the reduced neck 20 into and across chamber 16.

It will thus be seen that the portions 58 and 60, which project within chamber 18, are located forwardly of the washer 42 and abut thereagainst. When the handle 50 is pulled rearwardly the member 46 is also pulled rearwardly, so that the spring 40 is compressed from the position shown in Fig. 2 to that shown in Fig. 3.

Another spiral spring 64 is disposed within the upper chamber 16, adjacent the forward end thereof. The rear end of the spring 64 abuts against an in-struck tab 66, formed in the casing 14, and the forward end of the spring embraces a projection 68 formed along the rear edge of projection 62. Thus, as the member 46 is pulled rearwardly from the position shown in Fig. 2 to that of Fig. 3, the spring 64 is likewise compressed.

Means are provided for releasably engaging the washer 42 to hold the spring 40 in its compressed or loaded position, until released by the trigger. Such means include an elongated trigger lever 70, which is pivotally mounted to the casing by the pivot pin 72. The member 70 is provided with a longitudinally extending rib to stiffen the same, and the rear end projects within the frame portion 12 to a position above trigger 74. The trigger 74 is pivotally mounted to the casing by pivot pin 76 and has the usual depending finger engaging portion and also has upwardly extending fingers 78 which are alternatively disposed on opposite sides of member 70 so that such member is movably received therebetween. The rear edge of trigger 74 is provided with an upstanding projection 80 which is adapted to bear against flanges 82 formed on the under edge of member 70 at the rear thereof. As the trigger is pulled rearwardly, the projection 80 strikes against the rear end of lever 70 to move such rear end upwardly.

The rear end of member 70 is resiliently urged downwardly and the forward end of member 70 is urged upwardly by a spring member 84, which bears against the inside of the casing, is passed

through an opening 86 formed in member 70 and then extends forwardly and is hooked around the member 70 as indicated at 88.

It will thus be seen that the forward end of member 70 is resiliently urged upwardly and such forward end is offset downwardly so that it may be received within the member 46 as such member 46 slides rearwardly. The forward end of the lever 70 is provided with an upstanding projection 90, providing a shoulder 92 and having a rounded front corner 94. The top edge of the projection 90 is of a length greater than the distance between the adjacent convolutions of the spring 40 when such spring is extended, so that such spring will freely slide over the projection 90.

When the spring 40 is compressed to the position shown in Fig. 3, it will be seen that the projection 90 is snapped upwardly in front of washer 42 so that such washer is releasably engaged by the shoulder 92. The projection 90 extends inwardly beyond the peripheral edge of the washer 42 and extends through a slot 96 formed in tubular member 24. As soon as the washer 42 is engaged by the projection 90, the grip 50 may be released and the pump means, including the grip 50 and member 46, will be returned to their initial position shown in Fig. 2 through the action of the spring 64, and the parts will assume the positions shown in Fig. 4.

As stated above, the gun is adapted to shoot darts, and such darts may be of any desired form, but in the embodiment illustrated comprise a stem 100 of uniform diameter throughout the length thereof with a suction cup 102 secured to the forward end thereof. The dart is adapted to be positioned within the tube 24 as shown in Fig. 4, so that an inner end of the stem 100 abuts against the radial tab 44 of washer 42. As the shaft 100 is pushed inwardly to such position it will be seen that the projection 90, which projects into the tube 24 through the aperture 96, will be resiliently urged outwardly to a slight extent due to the fact that the inner end of the dart bears against the top edge of the projection 90. Such projection will thus be resiliently urged against the dart while the dart is in this position, through the action of the spring 84, so that the dart will be held in the gun and cannot accidentally drop therefrom.

When the trigger 74 is pulled, the projection 80 will raise the rear end of lever 70 so that the projection 90 will be withdrawn from engagement with the dart and the washer 42 so that the spring 40 will be released. The dart will then be projected from the gun by the thrust of the tab 44 against the inner end of the dart.

Formal changes may be made in the specific embodiment of the invention described, without departing from the spirit and scope of the invention, the scope of which is commensurate with the appended claim.

What is claimed is:

In a toy spring gun shaped to simulate a rifle and adapted to shoot darts, a sheet metal casing having a barrel portion, said barrel portion having upper and lower intercommunicating longitudinally extending chambers each of which is substantially circular in cross-section, the lower chamber being provided with a longitudinally extending slot in the underside thereof, a spiral spring mounted within said lower chamber adjacent the forward end thereof and compressible and expandable longitudinally thereof, another

spiral spring mounted within the upper chamber adjacent the forward end thereof and compressible and expansible longitudinally thereof, pump means including an elongated member having flanges formed on the upper edge thereof, said flanges being slidably mounted on the edges of said slot, said member having an upwardly extending projection at the front end thereof which projects through said lower chamber and into said upper chamber, said projection engaging both of said springs whereby both of said

5 springs are compressed when said member is slid rearwardly of said barrel, means releasably engaging said first named spring when said first named spring is compressed, the construction and arrangement being such that said another spring returns said member to its initial position after said first named spring is releasably engaged.
